SHUTTLE CHANGE MOTION FOR LOOMS.

Application filed May 6, 1924. Serial No. 711,363.

To all whom it may concern:

Be it known that we, ADOLPH WIDMER and FREDERICK W. VOGTMAN, citizens of the United States, residing at Paterson and Prospect Park, respectively, in the county of Passaic and State of New Jersey, have invented certain new and useful Improvements in Shuttle Change Motions for Looms, of which the following is a specification.

10 This invention relates to looms and in particular to that class of looms in which two or more rows or banks of shuttles are employed and are moved vertically so that any one row or bank may be positioned for a more or less length of time in operative relation to be received by the sheds of warp formed. Our object is to provide a so-called change-motion mechanism for effecting the shifting and positioning of the banks or 15 rows of shuttles which will be simple in construction and reliable in operation and readily applicable to any existing loom and which will be operated from the Jacquard or the like without calling into service for 20 this purpose more than one hook or equivalent element of the Jacquard and yet the mechanism may be adapted to control any number of banks or rows of shuttles.

25 In the drawings,

30 Fig. 1 is a side elevation of a loom embodying the invention;

Fig. 2 is a side elevation of so much of the loom as directly includes the invention;

35 Fig. 3 is a plan of what is shown in Fig. 2; Fig. 4 is a section on line 4—4, Fig. 2; and Figs. 5 and 6 illustrate details.

In the loom-frame *a* is arranged the bat-ten-including structure *b* reciprocated from the rotating crank-shaft *c* through the usual pitmen, one of which appears in Fig. 1 at *d*, and having suitably guided therein according to any well-known construction the vertically shiftable guiding structure *e* for the rows of shuttles *f* which are reciprocated therein, to cause the shuttles in the row which has been brought to the proper elevation for the purpose to pass through the shed of warp formed at *g*, by any means (not shown). The structure *e* is suspended at spaced points in its length from forward arms of a lever structure *h* (only the nearest forward arm is shown) from whose shaft *h'* at the near end thereof projects a rear-

ward arm *h*² which is connected with actuator-levers *j* by a link *k*, a pulley *l* journaled in the lower end of the link and a flexible connection *m* which is extended over the pulley and has its ends attached to the actuator-levers. There being four rows of shuttles in the present case and two actuator-levers and the latter being of different lengths any shuttle row may be brought into cooperative relation to the shed formed, i. e., according as one of the actuator levers is up and the other down, or vice versa, or both are up or both are down. There is nothing novel, however, in this, or any part in fact of the mechanism so far described. The improved change-motion mechanism is adapted to control any number of rows or banks of shuttles from two up (Figs. 2, 3 and 4 showing in fact three actuator-levers which when moved to the various relative positions possible would, with the employment of appropriate and well-known forms 70 of connections between them and the rocking lever *h*, control more than the four rows of shuttles seen in Fig. 1).

A fixed structure comprising a plate *n* and a laterally projecting bracket *n'* is bolted to the side of and may be treated as a part of the loom-frame. In this are journaled the spaced gears *o* *p* forming with two intermediate gears *q* *q* meshing with them and with each other a gear train; the gear *o* 80 meshes with a gear *c'* on the crank-shaft *c*. Following the usual construction in general but differing therefrom in certain details as will be later pointed out the gears *o* *p* have continuous toothed portions to intermesh with the gears *q* *q* and also mutilated portions, with which latter are adapted to cooperate in the well-known manner the vibrator crank-gears *r* which are journaled in vibrator-levers *s* fulcrumed in the frame at *t* 90 and each having the connector or link *u* connecting a crank-pin *r'* thereon with a corresponding actuator-lever *j*. Each vibrator-lever *s* has a slot *s'* in its free end which receives a pin *v'* on a pinion *v* which at one side has a rectangular portion *v*² against which bears a spring-pressed plunger *w* 100 slidable in the frame and adapted to hold the pinion in either of the two positions of half-rotation to which it is moved; the pinion *v* is journaled on a stud *x* which projects

from one of the vertical walls n^2 of structure n . Each pinion v meshes with a pinion y of twice its diameter and this pinion has four equidistant laterally projecting pins y' .
 5 It will thus be seen that if any pinion y be turned a quarter-revolution at a time the corresponding pinion v will be turned a half-revolution and so shift the vibrator-lever up or down, the parts being retained each
 10 time in the position to which they are thus moved by the pressure of the plunger w against two opposite sides of the portion v^2 of pinion v ; and the gear-train $o-q-q-p$ being constantly driven, on said parts as
 15 suming either of such positions one or the other of the gears $o-p$ will turn the vibrator crank-gear a half-revolution and leave it at dwell until said parts are made to assume the other position so that the other of
 20 said gears will turn the vibrator crank-gear back a half-revolution and leave it at dwell, thus moving the actuator-lever, through connector u , first one way and then the other.

25 Each pinion y is turned a quarter-revolution at a time by a pawl z which has a hooked lower end z' to engage the pins y' one after another and is adapted to be lifted intermittently by means, to be described,
 30 engaging its hooked upper end z^2 , the pawl having a tail z^3 which is connected by a spring 2 with the frame so that the pawl is normally held down and also in guided
 35 contact with a transverse supporting rail 3 affixed to the frame. The said pawl-lifting means is a U-shaped lever 4 fulcrumed, to move in a vertical plane, on the fixed projecting shaft 5 ; it has a longitudinal slot
 40 4^a in one arm thereof which receives a crank-pin 6 of the gear o . The lever 4 is thus made to reciprocate once for each revolution of the crank-shaft c (or each pick) of the loom, and if any pawl is shifted toward the lever so that its hooked upper
 45 end z^2 overlies the knife 4^b of the lever the pawl will rise with the lever and so on each such rise will catch with its hooked end z' the pinion y at one of the pins y' and turn the pinion a quarter-revolution, as stated.
 50 Pinion y forms in effect a ratchet.

The shifting of the pawls is controlled by indicator means constructed as follows: Each pawl is normally held by its spring 2 abutting a bell-crank lever 7 in the fork
 55 7^a of the latter, this lever being fulcrumed in a part of the bracket n' and itself normally abutting any suitable stop—here a pattern chain which is to be referred to. This lever 7 has an eye 7^b to which may be attached a wire or equivalent extending to a hook of the Jacquard machine of the loom. When this Jacquard hook “calls” the lever 7 , so that the lever is shifted and so shifts the pawl z into position to be caught by
 60 knife 4^b of lever 4 , the knife in rising will

elevate the pawl. By this arrangement as many different Jacquard hooks would be subject to service as there are pawls z to be operated. An important object of our invention is to reduce to one the number of hooks of the Jacquard thus subject to service, so as to reduce to the minimum the punching of the cards of the Jacquard machine in so far as the change-motion mechanism is concerned. To this end we employ a cylinder 8 journaled in the frame and over this extend a pattern chain 9 having a row of properly spaced “balls” or rollers 9^a to actuate each lever 7 , effecting the rotation of the cylinder and consequent advance of the chain as follows: A lever 10 is fulcrumed, to move in a vertical plane, on the fixed shaft 11 projecting from the structure n , and this carries an upstanding hook 12 pivoted thereto and normally held back by a spring 13 so as not to catch any of the four pins 8^a projecting laterally and equidistantly from the cylinder 8 . The hook 12 is received in the crotch of and held bearing by the spring 13 against the fork 14^a of a lever 14 which may be connected with a hook of the Jacquard machine by a flexible connection 15 . Whenever the Jacquard hook “calls” the lever 14 it shifts the hook 12 ; then on downward movement of the latter with lever 10 said hook will catch one of the pins 8^a and hence turn the pattern chain a one-quarter revolution. The lever 10 is made to reciprocate once for each revolution of the crank shaft c of the loom by receiving in a longitudinal slot 10^a thereof a crank pin 16 on the gear p . After each quarter-revolution of the cylinder 8 it is held at dwell by a spring plunger 17 which bears against a rectangular block or head 8^b on the cylinder.

The gears o and p are elongated cylinders each having at one end the hereinbefore mentioned continuous toothed portion, as shown at Figures 3 and 5, to intermesh with the adjoining gear q but having the remainder of its surface formed partially toothed and partially blank so as to properly cooperate as to this portion with the vibrator crank gears r . Each of these gears o and p has a bearing on a stub-shaft 18 (Fig. 5) projecting from the plate n and having a circumferential groove 18^a receiving a retaining screw 19 set in the gear. The outer end of each gear $o-p$ consists of a disk 20 having diametrically opposite arcuate slots 20^a which receive screws 21 tapped into the body of the gear; thus the disk may be adjusted rotatively with respect to the body of the gear. The disk has a diametric slot 20^b and in this is adjustable the crank pin 6 (or 16); that is to say, the crank pin (taking 6 for example) has a fixed collar 6^a to bear against the outer face of the disk and a nut 6^b screwed on its inner

end and coating with the collar to clamp the crank pin to the disk. The rotative adjustment of each disk with respect to the body of the gear is useful in timing the throw of the corresponding lever 4 or 10; the adjustment of the crank pin in the disk is useful in adjusting the extent of throw of such lever.

So far as we are aware the following 10 conspicuous features of our invention are new in this art, to wit: Given an oscillating actuating member (4) to rotate step by step through a pawl and ratchet means (as z y) the rotary means for vibrating a vibrator- 15 member as s , to provide for the shifting of the pawl into and out of engagement with the actuating member, whereby it remains at standstill in the periods when it is not engaged with said member. To provide, 20 with a ratchet-portion (as $y-y'$) of rotary means by which said member is vibrated, a pawl (z) for engagement with said ratchet-portion which is shiftable lengthwise in and guided by the frame and also shiftable lat- 25 erally of itself into and out of engagement with a going oscillatory part (as 4). To provide, with a plurality of vibrator members movable back and forth independently of each other, an oscillating actuator (4) 30 and means, one for each member, to transmit movement from the actuator to each of said members, means, including a moving pattern mechanism having pattern portions (9) respectively controlling the first-named 35 means, for rendering the respective first-named means functionally operative or inoperative to transmit such movement. And, finally, the adjustment possible at 20°.

Having thus fully described our invention, what we claim as new and desire to secure by Letters Patent is:

1. A shuttle change-motion mechanism for looms including, with the frame, a vibrator-member movable back and forth 45 therein from one to another position of rest, rotary actuating means for said member including a rotary member with which the first member is eccentrically connected and also including a rotary ratchet portion, a 50 pawl to engage said ratchet portion and thereby rotate said means intermittently in one direction, each time until said rotary member has turned a half-revolution, a going oscillating member for actuating the 55 pawl, said pawl being movable into and out of engagement with the oscillating member, and means to control said movements of the pawl into and out of engagement with the oscillating member.

2. A shuttle change-motion mechanism 60 for looms including, with the frame, a vibrator-member movable back and forth therein from one to another position of rest, rotary actuating means for said member including a rotary member with which the

first member is eccentrically connected and also including a rotary ratchet portion, a pawl to engage said ratchet portion and thereby rotate said means intermittently in one direction each time until said rotary member has turned a half-revolution, a going oscillating member for actuating the pawl, said pawl being movable into and out of engagement with the oscillating member, and pattern-controlled means to shift the pawl into engagement with the oscillating member.

3. A shuttle change-motion mechanism for looms including, with the frame, a vibrator-member movable back and forth 65 therein, rotary actuating means for said member including a rotary member with which the first member is eccentrically engaged and also including a ratchet portion, a pawl bodily shiftable lengthwise in and guided by the frame and also shiftable laterally of itself in the frame, means to control the lateral shifting of the pawl, and a going oscillating member, into engagement with which the pawl is laterally shiftable, 70 for shifting the pawl lengthwise, the pawl when shifted lengthwise being engageable with and adapted to rotate said ratchet portion.

4. A shuttle change-motion mechanism 75 for looms including, with the frame and with a pair of spaced going rotary gears and a third rotary gear arranged between and movable back and forth into geared relation to one or the other of the first-named gears, a vibrator-member in which the third gear is journaled and movable back and forth to shift the third gear into gear with one or the other of said first-named gears, rotary means to oscillate said member operatively 80 connected therewith, an actuating member operatively connected with and adapted to be oscillated by one of the first-named gears, means to transmit intermittent rotary movements to said rotary means from said actuating member shiftable into and out of engagement with the latter, and means to control the shifting of the last-named means.

5. A shuttle change-motion mechanism 85 for looms, including, with the frame and with a pair of spaced going rotary gears and vibrator crank-gears arranged between and movable back and forth into geared relation to one or the other of the first-named gears, vibrator-members in which the crank-gears are respectively journaled and movable back and forth independently of each other to shift the crank-gears into gear with one or the other of said first-named gears, independent rotary means to oscillate said members operatively connected therewith, a lever operatively connected with and adapted to be oscillated by one of the first two gears, separate devices, one for each ro- 90

tary means, to transmit motion from the lever to said rotary means and shiftable independently of each other into and out of engagement with the lever, and means to control the shifting of said devices.

6. A shuttle change-motion mechanism for looms, including, with the frame and with a pair of spaced going rotary gears and other rotary gears arranged between 10 and movable back and forth into geared relation to one or the other of the first-named gears, vibrator-members in which the said other gears are respectively journaled and each movable back and forth to shift the 15 corresponding gear into gear with one or the other of said first-named gears, an oscillating actuator, separate means, one connected to each member and movable into and out of connection with said actuator, to 20 transmit movement from the actuator to each of said members, means, including a movable pattern mechanism having pattern-portions respectively corresponding to said first-named means, for controlling the movements of said first-named means, an oscillating member operatively connected with 25 and adapted to be oscillated by one of the first-named gears, and pattern-controlled

means to move the pattern mechanism step by step.

7. A shuttle-change mechanism for looms including, with the frame and with a pair of spaced rotary gears and a third rotary gear arranged between and movable back and forth into geared relation to one or the other of the first-named gears, a vibrator-member in which the third gear is journaled and movable back and forth to shift the third gear into gear with one or the other of said first-named gears, an actuating member operatively connected with and adapted to be oscillated by one of the first two gears, and means, disconnectively connecting the actuating and vibrator members, to transmit actuation to the vibrator member from said actuating member, the part of the one of the first two gears with which said actuating member is connected being rotatively adjustable relatively to the part thereof with which the third gear is moved into gear.

In testimony whereof we affix our signatures.

ADOLPH WIDMER.
FREDERICK W. VOGTMAN.
